UNITED STATES PATENT OFFICE.

WILLIAM H. GEORGE, OF FAIRFIELD, IOWA, ASSIGNOR TO THE DEXTER COMPANY, A CORPORATION OF IOWA.

GEARING.

1,178,228.

Specification of Letters Patent.

Patented Apr. 4, 1916.

Application filed July 1, 1914. Serial No. 848,378.

To all whom it may concern:

Be it known that I, WILLIAM H. GEORGE, a citizen of the United States, and a resident of Fairfield, in the county of Jefferson and State of Iowa, have invented certain new and useful Improvements in Gearing; and I do hereby declare that the following is a full, clear, and exact description thereof, reference being had to the accompanying drawings, and to the letters of reference marked thereon, which form a part of this specification.

This invention relates to improvements in gearing, primarily intended for the operation of a wringer in connection with the operating shafts of power driven washing machines of the dolly or agitator type, and consists of the matters hereinafter described and more particularly pointed out in the appended claims.

The advantages of the improved gearing will appear as I proceed with my specification.

The gearing is shown herein applied to what is known to the trade as a bench washer, and in the case of the particular machine illustrated, there are provided two washing machines arranged side by side with a wringer located intermediate the tubs of the two washing machines in such manner that the clothes may be wrung from the tub of one washing machine into the tub of the other washing machine. In addition, the wringer is arranged to be swung from a position intermediate the tubs into positions for wringing from one or the other of the washing machine tubs into a basket or other receptacle supported on a platform hinged to the main bench which supports the said washing machines.

In the drawings: Figure 1 is a top plan view of a bench washer provided with my improved gearing. Fig. 2 is a view representing a vertical section through the said bench washer on an enlarged scale in a plane indicated by the line 2-2 of Fig. 1. Fig. 3 is a detail vertical sectional view through the parts shown in the upper left hand end of Fig. 2.

Referring now to that embodiment of my invention illustrated in the drawings, 10 indicates a bench adapted to support two washing machine tubs arranged side by side, to which bench is attached at one side a hinged platform 11 that may be raised into

a horizontal position adjacent to the bench. Said platform is provided with folding legs 11^a, 11^a, which may be swung down to support it in horizontal position when it is desired to use the said platform to support a basket or additional tubs.

12, 12 indicate washing machine tubs of a familiar construction, each having a hinged lid 13 to which is connected the usual depending dolly shafts 14, 14.

15, 15 indicate pinions fixed to the tops of said dolly shafts, and 16, 16, large horizontal gears engaged with said pinions and rotatively mounted on the hinged lids of the washing machine tubs.

17, 17 indicate aligned reciprocating rack bars operatively engaged with the gears 16, 16. Each rack bar 17 is mounted to slide on a rod 18 attached to a bracket plate 19, which is secured to the fixed top of the associated tub 12.

The dolly shafts of the two tubs are driven as follows: 20 indicates an upright, continuously rotating shaft located in a position intermediate the two tubs of the washing machines and in a vertical plane adjacent to the rack bars 17, 17. 21, 21 indicate pitmen which operatively connect the reciprocating rack bars 17 with a crank arm 22 at the top of the shaft 20. At the bottom of said shaft 20 is fixed a beveled gear 23. 24 indicates a horizontal drive shaft suitably supported in a vertical plane between the two washing machine tubs and having fixed to one end a driving pulley 25. The driving pulley 25 is adapted to be operated from any source of power, preferably an electric motor which may be carried by the bench 10 in a familiar manner. On the drive shaft 24 is fixed a beveled gear 26^x which operatively engages the beveled gear 23 to continuously rotate the upright shaft 20. Manifestly, the continuous rotation of the horizontal shaft 24 by means of the connection of the pulley 25 to the source of power will produce a continuous rotation of the shaft 20, which in turn will, through the crank arm 22 and the pitmen 21, 21, impart a longitudinal, reciprocatory motion to the rack bars 17 so as to impart an alternating, rotary movement to the dolly shafts of the washing machines.

26 indicates a wringer of familiar construction located in a vertical plane intermediate the two tubs 12, 12. Said wringer

is rigidly connected to a casing 27 which is 5 rotatively mounted on the top of a board 28 extending between and attached to the tubs of the washing machines. The casing 27 has a base plate 29 which has rotative bearing on a complementary plate 30 fixed to that end of the board 28 which is opposite to the position occupied by the power driven pulley 25. The casing 27 is provided 10 with a socket 31 to receive a pin 32 that is adapted to engage in suitable apertures, 33^a, 33^b, 33^c to lock the casing against horizontal swinging movement. The said apertures are so arranged that they will correspond to 15 positions of the casing when the wringer is located in a vertical plane between the two washing machine tubs and when it is located in a vertical plane between one or the other of said tubs and a basket or tub located on the platform when said platform 20 is in raised position.

In the casing 27 is mounted an upright continuously rotative shaft 34 which extends downwardly through the board 28 toward 25 the plane of the horizontal shaft 24. At its bottom end, said shaft is provided with a bevel gear 35. Said bevel gear engages a beveled pinion 36 on the end of the shaft 24 which is prolonged into the neighborhood 30 of the shaft 34. The upper end of the shaft 34 has bearing in and extends beyond the top of an upright tubular sleeve 30^a made integral with the plate 30 and the end 34^a of said shaft is squared and projects 35 into a like aperture formed axially within the hub 37^x of a gear 37. The bottom end of said hub has a thrust bearing on the top of said sleeve 30^a and a rotative bearing in the casing 27. The gear 37 engages reverse 40 gears 37^a, 37^b of familiar construction. Said gears are loosely mounted on a horizontal shaft 38 which is the operating shaft of the wringer.

39 indicates a clutch member feathered 45 to the shaft 38 and adapted for operatively connecting the one or the other of the gears 37^a, 37^b to said shaft 38.

40 indicates a controlling arm or lever pivoted to the casing 27 and adapted to operate 50 the clutch member 39 to bring it into position for operative engagement with either of the reverse gears 37^a, 37^b or into an intermediate, inoperative position, as indicated by the dotted lines. Any convenient 55 means may be provided for locking the controlling lever in either of its three positions, as for example, the arcuate arm 40^a.

Manifestly, the reverse gears 37^a, 37^b will be operated no matter into what position the 60 wringer is swung, so that the wringer may be driven in either direction in any position which it may occupy.

The upright shafts 34 and 20 are suitably supported at their bottom ends by means of 65 brackets, respectively, 34^a, 20^a, which may

be attached to the structure of the bench washer in any convenient manner.

It is apparent from the foregoing description that the wringer 26 and with it, the casing 27, may be removed as a whole 70 from the rest of the mechanism, by withdrawing the same in an upward direction. This construction is advantageous in that, when the machine as a whole is to be shipped, the wringer with its associated 75 reverse gearing may be bodily removed from its operative position on the washing machine and crated beneath the frame thereof upon which the tubs are mounted. When setting up the wringer it is only necessary 80 to place the wringer with its associated reverse gear casing upon the base 30 when it is then ready for use.

The construction and arrangement of 85 gearing shown and described is simple and cheap to manufacture, is efficient and has few parts to get out of order or to require replacement or repair. At the same time, 90 said parts are such that they are easily and rigidly supported in a structure of the kind for which they are primarily intended with a minimum of shock or jar to said structure that is likely to damage or weaken the parts of which it is made.

I claim as my invention:

1. In a gearing of the class described, in 95 combination with a main support, two horizontal supplemental supports hinged to said main support to swing about horizontal aligned axes, upright, alternating, rotary operating shafts carried by said supplemental supports, reciprocating rack bars adapted for driving said upright shafts, an upright, continuously rotating shaft located intermediate said supplemental supports, a crank arm at the upper end of said continuously rotating upright shaft, pitman rods operatively connecting said crank arm with said rack bars, a horizontal operating shaft rotatable in either direction and located intermediate said upright operating shafts, a third supplemental support carrying said horizontal operating shaft and mounted on said main support to swing in a horizontal plane, means for locking 100 said third supplemental support in predetermined horizontal positions, an upright second continuously rotating shaft with its axis co-axial with the axis about which said third supplemental support is adapted to swing, a gear at the upper end of said second continuously rotating shaft meshing with oppositely facing gears on said horizontal operating shaft, a clutch feathered 110 on said horizontal operating shaft adapted to coact with either of said oppositely facing gears, means for controlling said clutch to drive said horizontal operating shaft in either direction, and a main horizontal power driven shaft operatively connected 115 to said horizontal operating shaft.

to each of said upright, continuously rotating shafts.

2. In a gearing of the class described, in combination with a main support and horizontal supplemental support hinged thereto, an upright alternating rotary operating shaft carried by said supplemental hinged support, a continuously rotating power shaft on said main support, means operatively connecting said power shaft to said upright operating shaft whereby the continuous rotary movement of said power shaft is transposed into an alternating rotary movement of said operating shaft, a continuously rotating upright shaft journaled on said main support and driven by said power shaft, a horizontal operating shaft rotatable in either direction, a second supplemental support carrying said horizontal operating shaft mounted on said main support to swing in a horizontal plane about an axis coaxial with said continuously rotating upright shaft, a reverse gearing carried by said second supplemental support operatively connecting said horizontal operating shaft to said continuously rotating upright shaft, and means for controlling said reverse gearing, said second supplemental support with its associated shaft and gearing being capable of removal from said main support and from the driving influence of said continuously rotating upright shaft.

3. In a gearing of the class described, in combination with a main support and horizontal supplemental support hinged thereto, an upright alternating rotary operating shaft carried by said supplemental hinged support, a continuously rotating power shaft on said main support, means operatively connecting said power shaft to said upright operating shaft whereby the continuous rotary movement of said power shaft is transposed into an alternating rotary movement of said operating shaft, a continuously rotating upright shaft journaled on said main support and driven by said power shaft, a horizontal operating shaft rotatable in either direction, a second supplemental support carrying said horizontal operating shaft mounted on said main support to swing in a horizontal plane about an axis coaxial with said continuously rotating upright shaft, means for locking said second supplemental support in predetermined horizontal position, a casing carried by said second supple-

mental support, a reverse gear mechanism in said casing operatively connecting said horizontal operating shaft to said second upright shaft and means on said casing for controlling said reverse gear, said second supplemental support with its associated operating shaft, casing, reverse gear and control therefor being capable of removal from said main support and said upright operating shaft.

4. In a gearing of the class described, in combination with a main support and two horizontal supplemental supports hinged to said main support to swing about horizontal aligned axes, upright, alternating, rotary operating shafts carried by said supplemental supports, reciprocating rack bars adapted for driving said upright shafts, an upright, continuously rotating shaft located intermediate said supplemental supports, a crank arm at the upper end of said continuously rotating upright shaft, pitman rods operatively connecting said crank arm with said rack bars, a horizontal operating shaft rotatable in either direction and located intermediate said upright operating shafts, a third supplemental support carrying said horizontal operating shaft and mounted on said main support to swing in a horizontal plane, means for locking said third supplemental support in predetermined horizontal positions, a casing fixed to said third supplemental support, an upright second, continuously rotating shaft with its axis coaxial with the axis about which said third supplemental support is adapted to swing, reverse gearing in said casing operatively connecting said horizontal operating shaft and said second continuously rotating shaft together, said third supplemental support together with its associated shaft, casing, reversing gearing and locking means being capable of removal from said main support and second upright rotating shaft and a main horizontal power driven shaft operatively connected to each of said upright continuously rotating shafts.

In testimony, that I, claim the foregoing as my invention I affix my signature in the presence of two witnesses, this third day of June A. D. 1914.

WILLIAM H. GEORGE.
